GRASS SHEARS

John D. Beinert, Babylon, N.Y., assignor to International Patent Research Corp., New York, N.Y., a corporation of New York

Filed Feb. 10, 1965, Ser. No. 83,763

Term of patent 7 years

(Cl. D22—4)

FIG. 2

FIG. 4

FIG. 6

FIG. 1 is a three-quarter perspective view of a pair of grass shears, showing my new design;

FIG. 2 is a bottom plan view of the grass shears of FIG. 1;

FIG. 3 is an end elevational view of the grass shears of FIG. 1, taken from the left hand side thereof;

FIG. 4 is a three-quarter perspective view of my new design wherein both handle grips are textured and the upper handle is fashioned with a thumb guard thereon;

FIG. 5 is a bottom plan view of the grass shears of FIG. 4; and

FIG. 6 is an end elevational view of grass shears of FIG. 4, taken from the left hand end thereof.

The dominant portions of the design are shown in solid lines.

I claim:

The ornamental design for a grass shears, as shown and described.
